UNITED STATES PATENT OFFICE

1,943,032

METAL DRAWING PRESS

Nicolas Emilian Methlin, Paris, France, assignor
to Schneider & Cie., Paris, France, a company
of France

Application July 6, 1931, Serial No. 549,040, and
in France August 5, 1930

21 Claims. (Cl. 205—4)

The present invention relates to improvements in powerful metal drawing presses by means of which a previously punched blank is drawn out, that is to say a blank having the form of a cylinder with an end upon which the free end of the mandrel bears during the drawing operation.

It is known that such presses exist in which, for facilitating the engagement of the blank on the mandrel, the latter is jointed on its support in such a way that it can be moved to one side. These means permit the total size of the apparatus to be reduced on account of the fact that there is sufficient space for easily positioning the blank between the free end of the mandrel in its extreme withdrawn position and the drawing dies. On the other hand the jointing of the mandrel presents the serious disadvantage of permitting the mandrel to develop play in the joint and consequently make it very difficult to mount the blank on the mandrel, and also to centre the latter with respect to the draw plates during the course of the operation. In other words, the mandrel can not only yield (vertical direction) on account of the play in the joint but can also swing to the side.

Moreover, in the known drawing presses the die or draw plate holders are generally arranged at a suitable distance apart for the blank to be able to effect its complete travel through each die before engaging in the following die. This takes up a considerable amount of space which, in the case when four dies for example are employed, is considerably greater than three times the length of the blank, since the latter becomes lengthened after each drawing operation.

The improvements which form the subject of the present invention permit the above disadvantages of the known drawing presses to be removed; in particular, they permit the blank to be positioned easily and provide a considerable reduction in the space required by the use of a plurality of draw plates, while permitting use to be made of a non-jointed mandrel.

These improvements consist essentially in the use of a group of draw plates which can be moved out of the way with the cage in which the draw plate holders are mounted or without this cage, this withdrawing movement in any case allowing the blank to have free access to the end of the mandrel, the positioning of the blank on the mandrel being effected under these conditions, preferably according to a practical embodiment of the invention, by means of a blank supporting carriage which, when the draw plates have been moved out of the way alone or together with their

age, can travel freely on the frame of the press for the engagement of the blank and its removal.

In order to make the free travel of the blank supporting carriage possible in the case when use is made of a cage which cannot be withdrawn, that is to say a cage in which only the draw plates are movable in the cage with a view to moving them out of the way, this cage will, according to the invention, be constructed in the form of a yoke, that is to say without a lower base, the carriage then travelling freely through the yoke when the draw plates are moved out of the way.

Again according to the invention, the draw plate holders will be moved out of such a cage preferably in such a manner that this can be effected hydraulically, the draw plates being each adapted to be actuated separately, thus permitting them to be grouped in a small space and to be moved successively into the working position, the whole of the space necessary for the draw plates not utilized being available for the movement of the blank through the single draw plate which is in the working position.

The invention particularly comprises the use of a movable cross member forming an intermediate support for the mandrel, this cross member being adapted to be placed in varying positions according to the position occupied by the blank during the course of work, for example under the effect of a displacement by means of a hydraulic press.

One practical embodiment of the invention is illustrated by way of example in the accompanying drawings, in which:

Figures 1, 1^a, 1^b, and 1^c, when joined together, constitute a sectional elevation of a general arrangement taken along the longitudinal axis of a press comprising the improvements forming the subject of the invention.

Figures 2, 2^a, 2^b, and 2^c, when joined together, constitute a corresponding plan with parts in section.

Figure 3 is a cross sectional elevation taken along the line 3—3 in Figure 1^a.

Figures 4 and 5 are cross sectional elevations taken along the lines 4—4 and 5—5 respectively in Figure 1^b.

Figure 6 is an end view of the apparatus viewed from the right.

Figures 7 to 12 inclusive are diagrams illustrating modes of employment of the invention, Figures 7 and 7^a, and 11 and 11^a, when joined together, constituting single diagrams.

In these figures, A is a frame which, together

- with a foundation A¹, supports the whole of the apparatus. Upon the frame A rests the cage for the draw plate holders; this cage, in the example shown, is formed by two stirrups made in three parts B—B¹—B assembled with two longitudinal plates of side members B². The cage is connected by tie rods C to a support D secured to the foundation A¹. Two other tie rods E assist in maintaining the two stirrups B assembled together.
- 10 In the support D is or are guided in the known manner one or more plungers F upon which is attached a cross member G itself serving as a supporting and securing member for one of the ends of the mandrel H, not shown in Figure 2.
- 15 The plungers F work in press cylinders F¹ carried by a support F².

According to the invention the arrangement of the drawing dies or draw plates I¹—I²—I³—I⁴, varying in number as desired, may be withdrawn 20 in order to allow the free movement on the frame of a mechanism carrying the blank. The withdrawal in the example shown is produced with respect to the cage which is left fixed on the frame. For this purpose, the draw plate holders 25 with the draw plates they contain are guided in the longitudinal walls B² of the cage, as shown in the upper half of the plan section in Figure 2^a. The displacement of the draw plate holders in their guides is here obtained by means of hydraulic presses. Beneath each of the draw plate 30 holders are arranged, directly under the guides in the side plates B², press cylinders J (Figure 3), the pistons J¹ of which bear beneath the draw plate holders. These pistons, by lifting the draw plate holders, move in the interior of the walls B² so that, when the draw plate holders have been brought into the position shown in dot and dash lines in Figure 1^a, in view of the fact that the 35 portals or stirrups B of the cage comprise no cross members coupling them together at their lower part, a free path is then provided for the movement of the member carrying the blank.

In the example shown, and according to the invention, the blank-carrying member is formed 40 by a carriage K guided by ribs k in slots a in the frame (Figure 3). This carriage forms a support for two cradles L (omitted in Figure 2^a) upon which the blank M rests.

In order to permit the blank to be adjusted in 45 a vertical direction with respect to the mandrel, the cradles according to the invention are movable with respect to one another, and for this purpose they may be supported by pistons L¹ movable in press cylinders K¹ supported by the body K of the carriage. These press cylinders K¹ are supplied with liquid through telescopic pipes K², K³ together forming a piston, and the last element of which is movable in a fixed cylinder K⁴ receiving liquid through a duct K⁵. The body of the carriage K is rigid with two push rods 50 or sliders N guided on the frame A and on which may be engaged, in any one of the notches n, a cross member N¹ to which is coupled a push rod N² movable hydraulically, the rod N² being for this purpose rigid with a piston movable in a 55 press cylinder N³.

The carriage K is preferably combined with an abutment support O. The position of this support with respect to the carriage may be regulated by means of a connection comprising stretchers O¹ or any other analogous means.

The apparatus described permits the following operations to be carried out: If it is assumed that the disappearing draw plate holders are in place 60 in the position shown in full lines in Figure 1^a,

and the blank holding carriage is in the position shown in dot and dash lines in Figure 1, the presses J will be actuated by delivering liquid by means of a distributor not shown, so as to move the said draw plate holders into the inoperative position indicated in dot and dash lines in Figure 1^a. The path of travel is thus left free for the blank-holding carriage combined with the abutment stop O, the spacing of which with respect to the carriage will have been previously 80 adjusted according to the length of the blank to be drawn out. The arrangement formed by the carriage and this blank can travel through the cage forming a tunnel and be brought into place for engaging the blank upon the mandrel. This engagement may be carried out with very great ease since any eccentricity of the mandrel with respect to the blank can be corrected by a suitable adjustment of the position of one of the cradles L with respect to the other. In this way the blank, still in place on its cradle, will have been brought for example into the position shown in full lines in Figure 1^a. The successive positions 1, 2, 3 of the blank for its engagement are represented in the diagram shown in Figures 7 85 and 7^a.

After this operation has been carried out, the cradles L will have to be moved out of the way by cutting off the action of the liquid on the pistons of the press cylinders K¹, the lowering of 90 the cradles being facilitated if desired by the action of return springs l acting upon guide rods L², L³. The carriage which had been brought into position by a push exerted upon the sliders N through the medium of the cross member N¹ 100 may be returned backwards, by admitting liquid on to the opposite face of the control piston which moves in the press cylinder N³. The carriage will return so as to occupy the position shown in dot and dash lines in Figure 1^a.

According to the invention, the device described 110 permits the separate actuation of each of the draw plate holders so that the draw plates may alternately and successively be brought into the working position and then withdrawn.

The diagram given in Figure 8 shows the extreme right hand draw plate I¹ brought into its working position, while the draw plates I², I³, I⁴ 115 remain out of action. This diagram shows that the whole space occupied by the draw plates I², I³, I⁴ may be employed for the travel of the blank during the drawing operation through the draw plate I¹.

According to the invention the work, particularly on blanks of very great length, is facilitated without any risk of the mandrel yielding, by the use of a supporting cross member P movable on a guide which may be formed by the assembly cross ties C between the cage and the fixed support D. This cross member P may have 120 any suitable form, for example that indicated in Figures 1^b, 2^b and 5. The displacement of the cross member P may be obtained hydraulically by pistons P¹ movable in a press cylinder P² the control of which is again obtained by a suitable distributor, and will be independent from that of the mandrel carrying cross member.

When the work through the draw plate I¹ is completed, the mandrel H is returned backwards by suitably distributing the liquid in the actuating press. This backward return causes the draw plate to be extracted from the draw plate holder and the draw plate moves into the position indicated in Figure 9.

When the work has been completed with the 130

draw plate I^1 the corresponding draw plate holder is moved into the inoperative position, and the draw plate holder I^2 is moved into the working position with the draw plate it contains, so that the drawing operation can then be carried out through this draw plate, as shown in the diagram given in Figure 10.

All the operation described will be repeated in order to bring the draw plates I^3 and I^4 successively into the working position; all the draw plates are not necessarily employed, the number employed being dependent upon the dimensions and the temperature of the blank to be drawn.

15 The diagram given in Figures 11 and 11^a illustrates the operations for placing a blank of great length in position. As will be seen, the distance between the blank holder carriage K and the abutment support O has been adjusted accordingly.

The diagram given in Figure 12 illustrates the use which may be made of a draw plate holder as an abutment member for engaging the mandrel in a blank which has already been subjected to drawing operations, with a view to carrying out additional passes.

It will be understood that a blank which has already been subjected to considerable drawing no longer has sufficient clearance with respect 30 to the mandrel to permit it to be placed on the mandrel by merely pushing the blank against the mandrel by means of the carriage, whereas if the blank is supported on the carriage in abutting engagement with one of the draw plate holders, as shown in Figure 12, engagement may more easily be effected by moving the mandrel into the blank.

As indicated in the preamble to the description, one of the essential and characteristic features of the invention resides in the removal of the drawing members into an inoperative position, first of all together and then separately, the object of the simultaneous withdrawal being to leave the track free for the entry of a blank 45 holding member with a view to engaging the blank on a mandrel which will preferably be fixed.

This first withdrawal is moreover carried out preferably in conformity to the practical embodiment illustrated and described, but it may if desired be obtained by swinging, lifting or withdrawing the cage and its draw plates above the press or into a suitable channel, while the individual withdrawal of the draw plate holders out 55 of their cage permits different draw plates to be employed successively and alternately, in order to take advantage of the space occupied by the draw plates not employed at the moment in the drawing operation.

60 I claim:

1. A metal drawing press comprising a movable mandrel, a plurality of die holders fixed in the line of travel of said mandrel and adapted to support the drawing dies, and fluid pressure actuated means for selectively moving said die holders into and out of the path of said mandrel at will.

2. A metal drawing press comprising a longitudinally movable mandrel, a plurality of die holders each adapted to support a drawing die in the path of travel of said mandrel, said die holders being immovable in the line of travel of said mandrel, and means for moving each of said die holders independently of the others in a direction angularly related to the line of travel of 70 said mandrel whereby said holders and supported

dies may be selectively moved into and out of the path of said mandrel at will.

3. A metal drawing press comprising a longitudinally movable mandrel, a fixed cage member for supporting a plurality of drawing dies in the path of travel of said mandrel, a plurality of die holders slidably mounted in said cage, and means for moving each of said die holders independently of the others into and out of the path of said mandrel. 80

4. A metal drawing press comprising a horizontally movable mandrel, a fixed cage member for supporting a plurality of dies in the path of travel of said mandrel, said cage member being of an inverted U shape and having horizontally spaced vertical grooves in the sides thereof, a plurality of die holders slidably mounted in said grooves and each adapted to support a drawing die therein, and means for selectively moving said die holders vertically into and out of the path of said mandrel. 95

5. A metal drawing press comprising a movable mandrel, a cage member for supporting a plurality of drawing dies in the path of travel of said mandrel, a plurality of die holders slidably mounted in the walls of said cage and each supporting a drawing die therein, and means for moving said die holders into and out of the path of said mandrel including fluid pressure actuated pistons engaging said die holders and moving wholly with 100 in the confines of the walls of said cage.

6. A metal drawing press comprising a horizontally movable mandrel, a fixed cage member for supporting a plurality of dies in the path of travel of said mandrel, said cage member being of an inverted U shape and having horizontally spaced vertical grooves in the sides thereof, a plurality of die holders slidably mounted in said grooves and each adapted to support a drawing die therein, and fluid pressure actuated means for moving 110 said die holders vertically into and out of the path of said mandrel including a cylinder mounted beneath each of said grooves in the sides of said cage, pistons for said cylinders the upper ends of which are adapted to engage the bottoms 115 of said die holders and means for supplying fluid under pressure to said cylinders to raise said pistons and die holders, said pistons moving wholly within the confines of said grooves.

7. A metal drawing press comprising a mandrel, 125 a blank supporting carriage movable relatively to said mandrel, a plurality of die holders interposed between the normal positions of said carriage and mandrel and each adapted to support a drawing die in the path of travel of said mandrel, 130 a fixed cage in which said die holders are mounted, means for moving said die holders and supported dies out of the path of said mandrel, and means for moving said carriage into the space normally occupied by said die holders and into 135 juxtaposition with said mandrel to place the blank thereon.

8. A metal drawing press comprising a cage member adapted to support a plurality of drawing dies, a plurality of die holders slidably mounted in said cage, a mandrel positioned on one side of said cage member, a blank supporting carriage normally positioned on the other side of said cage member and movable relatively thereto, means for moving said die holders out of the path of said 140 carriage, and means for moving said carriage into the space normally occupied by said die holders and into juxtaposition with said mandrel to place the blank thereon. 145

9. A metal drawing press comprising a man- 150

- 5 drel, a cage member for supporting a plurality of dies in the path of travel of said mandrel, said cage member being of an inverted U shape and having a plurality of die holders slidably mounted in the sides thereof, a blank supporting carriage normally positioned on the side of said cage member opposite to said mandrel and capable of movement relative thereto, means for moving said die holders out of the path of said mandrel, and means for moving said carriage into the space normally occupied by said die holders and into juxtaposition with said mandrel to place the blank thereon.
- 10 15 20 25 30 35 40 45 50 55 60 65 70 75 80 85 90 95 100 105 110 115 120 125 130 135 140 145 150
16. In a metal drawing press, a fixed frame with a die and a mandrel supported thereon in normally coaxial alignment, and means for placing a blank to be drawn upon said mandrel comprising a blank supporting carriage mounted on said fixed frame, and means for moving said carriage relatively to said frame and die and into juxtaposition with said mandrel to place the blank thereon, and for returning said carriage to its original position prior to commencement of the drawing operation.
17. In a metal drawing press, a fixed frame with a die and a mandrel supported thereon in normally coaxial alignment, and means for placing a blank to be drawn upon said mandrel comprising a blank supporting carriage mounted on said fixed frame, and fluid pressure actuated means for moving said carriage relatively to said frame and die and into juxtaposition with said mandrel to place the blank thereon, and for returning said carriage to its original position prior to commencement of the drawing operation.
18. In a metal drawing press, a fixed frame with a die and a mandrel supported thereon in normally coaxial alignment, and means for placing a blank to be drawn upon said mandrel comprising a carriage mounted on said fixed frame, blank supporting cradle means carried by said carriage, means for moving said carriage relatively to said frame and die and into juxtaposition with said mandrel to place the blank thereon, and for returning said carriage to its original position prior to commencement of the drawing operation, and means for adjusting the position of said cradle means relatively to said carriage whereby the position of the axis of the supported blank may be varied relatively to the axis of the mandrel.
19. In a metal drawing press having a fixed frame with a die and a mandrel supported thereon, means for placing a blank to be drawn upon said mandrel comprising a carriage mounted on said fixed frame, blank supporting cradle means carried by said carriage, means for moving said carriage relatively to said frame and die and into juxtaposition with said mandrel to place the blank thereon, and for returning said carriage to its original position prior to commencement of the drawing operation, and fluid pressure actuated means for adjusting the position of said cradle means relatively to said carriage whereby the position of the axis of the supporting blank may be varied relatively to the axis of the mandrel.
20. In a metal drawing press having a fixed frame and a mandrel supported thereon, means for placing a blank to be drawn upon said mandrel comprising a carriage mounted on and guided by said fixed frame, means for moving said carriage relatively to said frame and into juxtaposition with said mandrel, and means for supporting a blank upon said carriage including a cradle member carried by said carriage, a piston connected to said cradle member and housed in a cylinder mounted on said carriage, and means for subjecting said piston to the pressure of a fluid medium whereby the position of said blank supporting cradle member may be adjusted with respect to said carriage and to the axis of the mandrel.
21. In a metal drawing press having a fixed frame and a mandrel supported thereon, means for placing a blank to be drawn upon said mandrel comprising a carriage mounted on and guided by said fixed frame, means for moving said carriage relatively to said frame and into juxtaposition with said mandrel, and means for supporting a blank upon said carriage including a pair of cradle members carried by said carriage, fluid pressure actuated means for raising and lowering said cradle members with respect to said carriage, and return spring means for resiliently urging said cradle members to their lowermost positions.
22. In a metal drawing press having a fixed frame with a die holding structure and a mandrel supported thereon, means for placing a blank to be drawn upon said mandrel comprising a blank supporting carriage mounted on and guided by said fixed frame, means for moving said carriage relatively to said frame and die holding structure and into juxtaposition with said mandrel, and means for abutting the closed end of said blank and preventing longitudinal displacement thereof with respect to said carriage while said blank is being placed upon said mandrel.
23. In a metal drawing press having a fixed frame with a die holding structure and a mandrel supported thereon, means for placing a blank to be drawn upon said mandrel comprising a carriage mounted on said fixed frame and adapted to support a blank thereon, an abutment member adjustably connected to said carriage and adapted to abut one end of said blank, and means for moving said carriage and connected abutment member as a unit relatively to said frame and die holding structure and into juxtaposition with said mandrel.
24. A process of drawing metal in a machine having a plurality of dies arranged in series including the steps of moving all of the die holders out of their normal positions in the path of travel of the mandrel, moving a blank through the space normally occupied by said die holders and placing the same upon the mandrel, returning one of said die holders to operative position, moving the mandrel to force the work completely through the die supported in said holder, reversing the direction of movement of said mandrel and returning it to its starting position, said reverse movement removing said die from its holder and placing it on the mandrel, moving another die holder into operative position, and repeating the drawing operation.
25. In a metal drawing press, a mandrel, a cage member for supporting a plurality of closely adjacent drawing dies for cooperation with said mandrel, a plurality of die holders slidably mounted in said cage member, means for selectively moving said die holders into and out of operative position, each of said die holders supporting a die which is removable therefrom by backward movement of the mandrel after the work has been forced therethrough, and means for alternately moving said mandrel forward and backward whereby the work is subjected to a succession of complete drawing operations without removal from the mandrel.

20. A metal drawing press comprising a mandrel, a cage member for supporting a plurality of drawing dies for cooperation with said mandrel, means for moving said mandrel and cage member relatively to one another, a plurality of die holders slidably mounted in said cage member, and means for selectively moving said die holders into and out of operative position, each of said die holders supporting a die so constructed and arranged as to be fixed with respect to said holder during the time that the mandrel is forcing the work through the die but to be removed from said holder upon reversal of the relative movements of said mandrel and cage member and thereafter supported by said mandrel.

21. A metal drawing press comprising a mandrel, a cage member for supporting a plurality of drawing dies for cooperation with said mandrel, means for moving said mandrel and cage member relatively to one another, a plurality of die holders slidably mounted in said cage member, and means for selectively moving said die holders into and out of operative position, each of said die holders supporting a die so constructed and arranged as to be fixed with respect to said holder during the time that the mandrel is forcing the work through the die but to be removed from said holder upon reversal of the relative movements of said mandrel and cage member and thereafter supported by said mandrel.
